BATHING CAP

Betty A. Williams, Chicago, Ill.

Application February 10, 1950, Serial No. 7,863

Term of patent 7 years

(Cl. D3—15)

To all whom it may concern:

Be it known that I, Betty A. Williams, a citizen of the United States, residing at Chicago, in the county of Cook and State of Illinois, have invented a new, original, and ornamental Design for a Bathing Cap, of which the following is a specification, reference being had to the accompanying drawing, forming part thereof.

I claim:

The ornamental design for a bathing cap, as shown and described.

BETTY A. WILLIAMS.
